[57] CLAIM

The ornamental design for a bicycle fairing, as shown and described.

DESCRIPTION

FIG. 1 is a front and right side perspective view of a bicycle fairing showing our new design, it being understood that the broken lines are for illustrative purposes only and form no part of the claimed design;

FIG. 2 is a top plan view thereof;

FIG. 3 is a front elevational view thereof;

FIG. 4 is a bottom plan view thereof;

FIG. 5 is a rear elevational view thereof; and,

FIG. 6 is a right side elevational view thereof, the opposite side thereof being identical.

FIG-2

FIG-3

FIG-4

FIG. 5

FIG. 6
